ELECTRIC SWITCH

Herman John Hammerly, New Britain, Conn., assignor to The Trumbull Electric Manufacturing Company, Plainville, Conn., a corporation of Connecticut

Application January 3, 1938, Serial No. 182,996

5 Claims. (Cl. 200—168)

My invention relates particularly to switches of the so-called enclosed or safety type having quick make and break mechanism.

One object is to provide a switch of this type having the switch mechanism per se assembled as a unit and readily insertable and removable as such into and from a switch box and having the quick make and break mechanism fixed in the box, the connections between the switch mechanism and the quick make and break mechanism being such that the parts are automatically brought into operative relation by the mere insertion and fastening of the switch unit in the box.

Another object is to provide a manually operable enclosed switch having no parts projecting laterally from the sides of the box.

Another object is to provide a self indicating type of actuating mechanism so that the operator or inspector can readily tell whether the switch is "on" or "off."

Another object is to provide an enclosed switch with a front type handle and actuating mechanism carried by the box body independently of the cover.

Another object is to provide an enclosed switch with the cover handle, switch operating handle and cover latch on the same plane.

Another object is to provide guide means for properly positioning the switch unit in the box.

In carrying out the invention I mount the switch unit and circuit protecting devices upon a base plate which is insertable into the open box and secured to the bottom of the box by screws which fit into keyhole slots or the like.

The box may be of the usual type with a cover hinged along one side edge and provided with a handle and latch at the opposite side.

The switch actuating mechanism preferably of the quick make and quick break type is mounted upon one side wall of the box and provided with an operating handle which projects from one corner of the box, the corner of the cover being cut away to clear the handle. Interlocking means is preferably provided between the switch actuating mechanism and the cover of the box so as to normally prevent opening of the cover when the circuit is closed and so as to normally prevent closing of the circuit when the cover is open. The interlocking mechanism, however, may be readily retracted so as to permit manual operation of the switch by the simple insertion of a tool through a slot in a wall of the box. The handle for the cover is at the lower end

of the box and the handle for the switch is at the upper end.

Fig. 1 is a front view of a switch embodying my invention, the cover being shown closed and the switch operating handle or lever being shown in the "off" position.

Fig. 2 is a side view of the same.

Fig. 3 is a front view showing the cover of the box opened out, the protective fuses however being omitted.

Fig. 4 is an end view of the removable switch unit.

Fig. 5 is a bottom plan view of the same, a part being broken away.

Fig. 6 is an interior side view showing the switch actuating mechanism on the side wall of the box, said parts being shown in the "off" position.

Fig. 7 is a similar view showing the parts in the "on" position.

Fig. 8 is a sectional view through the hub of the quick make and break device on the side wall of the box.

In the usual and preferred form of the invention the box 10 may be formed of sheet metal and provided with a cover 11 hinged at 12 on one of the side walls. A spring pressed latch 13 is usually provided to hold the cover closed and a handle 14 is provided to facilitate opening the cover. The latch 13 is mounted on the wall of the box opposite the hinges 12.

The operating handle 15 is pivoted at 16 inside on one wall of the box and adjacent one corner thereof. The edge 17 of the box opposite the hinges is preferably flanged over and slotted as at 18 and 18' to allow for the latch 13 and the handle 15. The handle is provided with an arcuate portion 19 which is adapted to bear indications as to the "on" and "off" positions. This portion 19 is provided with a number of perforations 20 for the insertion of locking or sealing devices.

A correspondingly shaped flange 21 is also preferably secured to the box and provided with openings 22 adapted to register with the openings 20 for the reception of the sealing or locking devices. This flange may conveniently be formed as an integral part of a reinforcing angle member 23 secured to the wall of the box adjacent the handle. The corner of the cover is cut away at 24 to clear the handle and its arcuate portion 19. It will be seen that this arcuate portion always closes the slot 18' in the flange of the box.

The switch mechanism proper is shown as having an actuating crank shaft 25 whose ends 26

and 27 are suitably pivotally supported. This crank shaft has at one end an arm 28 which extends beyond the wall of the switch unit and is adapted to be slid into engagement with a part 5 of the quick make and break actuating mechanism mounted on the wall of the box.

This mechanism includes an oscillating disc 30 which is mounted to turn on the stationary bearing 31 mounted on the side wall of the box. This disc 30 has projecting spaced apart lugs such as 32 as is customary in quick make and break mechanisms.

The throwing spring 33 is mounted on a rod 34 which has one end hinged to the disc 30 in 15 any suitable manner and its other end projecting loosely in a bracket 34' on the side wall. An actuating disc 35 is also mounted on the bearing 31 between the disc 30 and side wall and is provided with a lost motion slotted connection 20 with the disc 30 for instance by means of rivets 36 which are secured to disc 30 and extend into slots in the disc 35 in the customary manner. This disc 35 is connected by link 37 to the inner 25 part of the handle 15 so that when the handle is moved from the position shown in Fig. 6 to the position shown in Fig. 7 or vice versa, the disc 35 will be given a corresponding rotation but in the reverse direction and cause the quick make and break device to operate and thus through 30 the medium of the crank shaft open and close the circuit of the switch in the usual manner.

It will be noted that the quick make and break mechanism and the actuating mechanism are all mounted on one wall of the box.

I also preferably provide suitable interlocking mechanism including for instance a latch 40 mounted on a hinge pin 41 in the side wall of the box and provided with a slot to permit the latch to have not only a rotative motion about the 40 pivot 41 but a swinging motion for retracting purposes as will be understood. This latch has a hook portion 42 adapted to interlock when the cover is closed with a pin 43 carried by the cover. The wall of the box is slotted at 44 to permit the pin 43 to pass. The latch is also provided 45 with an inclined part 45 adapted to be engaged by the pin 43 when the cover is closed so as to hold the latch in the position shown in Fig. 7 where the inner end of the latch 46 is held retracted from the locking disc 47 which is mounted 50 on the bearing 31. A spring 48 connected to the latch 40 and to the box wall biases the latch toward the positions shown in Figs. 6 and 7.

When the parts of the switch are in the "on" 55 position and the cover is closed as shown in Fig. 7 the cover is held closed by the engagement of the hook 42 with the pin 43. I preferably provide, however, a slot 49 in the wall of the box 60 adjacent the latch 40 through which a tool such as the tip of a screw-driver may be inserted to engage the latch and retract the hook 42 from the pin 43 and permit the cover to be opened so that the switch may be inspected.

When the cover is open and the parts of the 65 switch are in the "off" position the inner end 46 of the latch 40 interlocks with the disc 47 and normally prevents the actuation of the switch to close the circuit. The latch may, however, be readily retracted by the insertion of an implement into the slot 44 so as to engage the part 42 and tilt the latch about its hinge pin 41 so as to disengage the inner end 46 from the locking disc 47.

The switch contacts and protecting devices

therefor and actuating crank are carried as a unit by a frame-work including a back plate 50. This plate preferably has a flange 51 which supports the bearing for one end 27 of the crank shaft. Another flange 52 secured to this back 5 plate supports the end 26 of the crank shaft. The stationary and movable contacts of the switch are carried by an insulating block 53 which also supports the clips for the circuit protecting devices. A second insulating block 54 carries 10 the other clips. These insulating blocks are supported on channel-like members 55 and 56 which are secured to the back plate 50.

The back plate is provided with a number of keyhole shaped openings or slots 57, the slots 15 being slightly slanted, to receive the screws 58 which are seated in the back wall of the box and guide the back plate to proper position. When the screws 58 are loosened it will be seen that the back plate may be readily slid toward the left 20 as viewed in Fig. 3 sufficiently to disengage the crank 28 from between the lugs 32 whereupon the back plate with all of the attached parts of the switch and protective devices may be removed by drawing the back plate from the front of the 25 box. The same or another switch unit may be inserted and secured in place in a reverse manner. As the slots are somewhat inclined the weight of the switch block and attached parts tends to hold them in place even if the screws 30 work loose.

It will thus be seen that the switch mechanism per se may be constructed and tested as a unit before insertion in the box or quickly replaced as a unit in case of damage to any of the parts. 35 Similarly the switch actuating mechanism may be constructed and the parts assembled in the box and tested independently of the switch contact parts.

As the switch box has no projections from the 40 sides it will be seen that a number of these switches may be mounted in a bank side by side in a minimum space. This type of construction also requires a minimum of shipping space and a minimum of packing because of the absence of 45 lateral projections. This type of construction also lends itself to convenient operation either by hand or by means of an extension such as a pole frequently required when switches are to be mounted high up on the wall or in places not 50 readily accessible. Although this may in a certain sense be regarded as a front operated switch, it will be seen that none of the switch or operating parts are carried by the cover. It will also be noted that the cover handle, the switch actuating handle and the interlocking latch are all positioned on the same side of the box when the 55 cover is closed.

I claim:

1. An enclosed switch including a box having 60 rear and side walls, a switch unit on the rear wall including stationary and movable switch members and an actuating crank shaft and quick make and break mechanism fastened as a unit on one of the side walls including an operating 65 handle and a movable disk member adapted to actuate said crank shaft, said switch unit being attachable and detachable independent of and without interference with said quick make and break mechanism.

2. An enclosed switch including a box having 70 rear and side walls, a readily detachable switch unit on the rear wall including stationary and movable switch members and an actuating crank shaft and quick make and break mechanism in- 75

cluding an operating handle and a movable disk member adapted to actuate said crank shaft, said quick make and break mechanism being fastened as a unit on the inner side of one of the side walls.

3. An enclosed switch including a box having rear and side walls, inwardly extending studs on the rear wall, a switch unit on the rear wall including stationary and movable switch members and an actuating crank shaft, and quick make and break mechanism fastened as a unit on the inner side of one of the side walls including an operating handle and a movable disk member having spaced lugs adapted to engage the crank shaft for moving the same, said switch unit being attachable and detachable as a unit independent of and without interference with said quick make and break mechanism, said studs and spaced lugs being so arranged relatively that attachment of the switch unit to the studs automatically positions the crank shaft in operative relationship with the spaced studs.

4. An enclosed switch including a box having rear and side walls, a switch unit on the rear wall, a cover hinged to one of said side walls adjacent its upper edge, an inwardly extending flange on the upper edge of the opposite side wall and having an opening, an arcuate-shaped flange on the same edge adjacent said opening and extending at right angles to the first named flange, quick make and break mechanism on said last named side wall having an operating member with an arcuate-shaped portion and a handle portion, said arcuate-shaped portion extending

outwardly through said opening and substantially filling said opening and said handle projecting forwardly of the box within the outer boundary of its supporting side wall, said arcuate-shaped flange having spaced openings and the arcuate-shaped portion of the operating member having openings adapted to be moved into alignment with the openings in said flange for receiving a seal.

5. In an enclosed switch, a box with side and rear walls, headed stud members on the rear wall and protruding inwardly of the box, a switch unit detachably secured to the stud members, a quick make and break mechanism fastened as a unit on the inside of one of the side walls including an operating member, said switch unit including a supporting plate having slots therein for receiving said headed studs, stationary and movable switch members secured to said plate and a crank shaft for actuating said movable members, each of said slots being shaped substantially like a key-hole slot and being elongated transversely relative to the side of the box, one edge of the slot having a slanting portion between the larger and smaller portions of the slot so that when positioning the switch unit in the box the slots and studs coat in such a way that the studs have a tendency to seat themselves in the smaller portion of the slot thereby guiding the switch unit to proper position and insuring proper engagement between the operating member and the crank shaft.

HERMAN JOHN HAMMERLY.
